UNITED STATES PATENT OFFICE.

WILLIAM L. MCGRATH, OF ELMIRA, NEW YORK, ASSIGNOR TO ECLIPSE MACHINE COMPANY, OF ELMIRA, NEW YORK, A CORPORATION OF NEW YORK.

ENGINE STARTER.

Application filed November 5, 1923. Serial No. 672,910.

My invention has relation to means for starting or cranking an engine such as an internal combustion engine, and more particularly to that part of the engine starter system known as the drive or transmission which transmits the power of the prime mover such as an electric motor to a member of the engine to be started such as the fly-wheel thereof, such drive being capable of manual operation for engagement with the engine member and of automatic disengagement therefrom when the engine operates under its own power. In the practice of my invention, a driving member such as a pinion which is adapted to engage or mesh with the engine member cooperates with a spring adapted to hold such pinion in a normal position upon its shaft and the object of my invention is to provide means whereby the pressure or tension of this spring may be varied according to the different relative positions of the pinion on its shaft, in particular to lessen the tension of the spring at the time of the disengagement of the pinion from the engine member or fly-wheel when there should be substantially no resistance encountered by the pinion in its longitudinal movement for that purpose, and to increase the tension of such spring against the pinion when disengaged and held in retracted position on its shaft, so as to insure the return of the pinion to its normal position.

In the drawings, Figure 1 is an elevation partly in section of the engine starter system embodying my invention and showing the parts in their normal or disengaged position; Fig. 2 a view similar to Fig. 1 but illustrating the parts in engaged position; Fig. 3 a view similar to Fig. 2 but showing the pinion in disengaged position and the manual shift mechanism still in operated or shifted position; Fig. 4 a view similar to Fig. 1 except that the pinion is shown at its innermost position just before its shaft has been returned to normal position to release such pinion from its retained position shown; Fig. 5 a longitudinal section of the parts as shown in Fig. 1; Fig. 6 a detailed view of the part of the shaft or sleeve; Fig. 7 a view of one end of the pinion; Fig. 8 a cross section of the pinion on the lines 8-8 of Fig. 7; Fig. 9 a sectional elevation on the line 9-9 of Fig. 5; Fig. 10 a sectional elevation of a starter system embodying a modified form of construction; Fig. 11 a de-

tailed view of the shaft and the spring retainer; Fig. 12 a longitudinal section of the shaft.

For the purpose of a clear and definite disclosure of my invention, I have shown the same embodied in two different constructions of drive, one being illustrated in Figs. 1 to 9 and the other in Figs. 10 to 12, but it will be understood that such invention may be embodied in structures of somewhat different formation and arrangement, without departing from the spirit and scope of my invention. It will also be understood that while I have shown my invention incorporated in a so-called outboard type of drive and also in the direct type of drive, the same may be incorporated in the inboard type and also in the indirect type of drive.

Referring to the particular embodiment of my invention as illustrated in Figs. 1 to 9, the prime mover is an electric motor 1 which is provided with an extended armature shaft 2 having a suitable bearing 3 at its outer end. This motor is provided with a suitable switch and the usual electrical connections (not shown) which are preferably actuated by the manual or pedal shift connections hereinafter described.

Upon the driving or armature shaft 2, there is mounted a hollow shaft or sleeve 4 for rotary movement with the armature shaft and for longitudinal movement thereon. This hollow shaft may be made in one piece or in two pieces as shown in Fig. 5, with one piece provided with a screw threaded portion 5. As shown, this sleeve which may be termed a screw-shaft, is splined to the armature shaft by means of the cooperating splines 6 which are indicated more clearly in Figs. 5 and 12. The screw-shaft is provided at its inner end with the parallel collars or flanges 7 as either separate or integral parts which flanges form an intervening circumferential groove 8 with which cooperates the rollers 9 of suitable shifting means. Such shifting means are here shown as a lever 10 pivoted upon a suitable shaft 11 and actuated by the operator by hand or foot, the precise construction of such shifting means being non-essential to the practice of my invention.

The driving member is here in the form of a pinion 12 adapted to mesh with the teeth of the flywheel 13 and threaded upon the sleeve or screw-shaft. This pinion is nor-

mally positioned at the outer end of the screw-shaft and against the stop nut 14 as shown in Fig. 1, and is held in this normal position by means of the coil spring 15 which 5 encircles the screw shaft and normally bears against the inner face of the pinion or against an interposed spring abutment 16. The object of my present invention is to provide means whereby this spring is capable 10 of imparting to the pinion different degrees of pressure or tension according to the different periods in the cycle of operation, that is according to the different relative positions of the pinion upon its screw-shaft and of the 15 screw-shaft upon the armature shaft.

To this end, the armature shaft is provided with a suitable abutment for the inner end of the spring, such abutment here consisting of a pin 17 extending transversely 20 of the armature shaft and passing through longitudinal slots 18 in the sleeve 4 and extending therebeyond at both ends. Such abutment also comprises a flanged plate 19 having a central opening whereby it slips 25 upon the sleeve and having a circumferential groove 20 to receive the innermost coil of the spring. This plate is suitably shaped as shown in order to keep the pin in place, such pin being removable for dis-assembly purposes. 30 This plate is held against the pin 17 in all the different longitudinal positions of the sleeve as shown by Figs. 1 to 5.

A cup or drum 21 is secured to the sleeve and thereby moves in unison therewith, the 35 spring 15 at its inner end encircling such drum. Within this drum, there is pivoted in the slot 22 of the screw-shaft and upon the pivot pin 23 a latch 24 whose outer end is adapted to engage a notch 25 in the inner 40 end of the bore of the pinion to thereby hold such pinion in a retracted position such as shown in Figs. 3 and 4. This latch is spring pressed to operative position by means of the coil spring 26 interposed between the inner 45 end of the latch and the interior of the drum 21. In the inoperative position shown in Fig. 5, such inner end of the latch bears against the periphery 27 of the armature shaft but when the sleeve is moved out- 50 wardly along the armature shaft such end of the latch is forced downwardly by the spring pressure and slides down the sloping shoulder 28 and upon the reduced portion of the armature shaft between the splines 55 and the outer end of the latch is moved upwardly. The latch is thereupon in position for engagement with the pinion whenever the latter comes within its range. This retaining mechanism per se forms no part 60 of my present invention, but is concerned therewith because it occasions one of the conditions or positions of the pinion which is taken care of by the spring 15.

Describing a cycle of operation of my engine starter system and beginning with the

parts in their normal position shown in Fig. 1, when the operator actuates the shifting means the drive assembly is shifted longitudinally along the armature shaft to the position shown in Fig. 2, at which time the current is supplied to the starting motor 7 either automatically as an incident to the actuation of the shifting means or by a separate operation. The spring 15 which had been under some compression in its normal position shown in Fig. 1 now expands to the position shown in Fig. 2, at which time it exerts practically no resistance or pressure upon the pinion. The drive parts are now in cranking position and when the engine has been 70 cranked and operates under its own power, the pinion will be automatically demeshed due to the fact that the pinion is screw threaded upon its shaft.

Immediately upon the starting of the engine, the operator should release the shifting means which will be returned in the usual way to normal position and the pinion will be demeshed by reason of its screw action upon its shaft, but in the event that he does 80 not do so, the parts will thereupon be in the relative position shown in Fig. 3 in which the pinion is shown demeshed from the flywheel, but engaged by the latch.

Fig. 4 shows the positions just before the final return movement of the sleeve is completed. This final return movement causes the inner end of the latch 24 to ride up the slope 28 and upon the periphery 27 of the armature shaft, thereby withdrawing such latch from the pinion and permitting the latter to move spirally to normal position as shown in Figs. 1 and 5. In the position shown in Fig. 4, the spring 15 becomes compressed and such pressure is utilized in forcing the pinion to move spirally to normal position in the manner described inasmuch as the screw threads have a comparatively long lead.

Thus means are provided for varying the tension of the spring 15 according to different phases of the cycle of operation to thereby exert different pressures upon the pinion. When the parts are in the relative position shown in Fig. 4, at which time the pinion requires its maximum amount of spring pressure, the tension of the spring is at maximum. When, however, the pinion is in mesh with the flywheel and is about to be demeshed, as shown in Fig. 2, the spring pressure thereupon is then at a minimum, inasmuch as the spring tension is at a minimum or practically nothing. Therefore, the demeshing of the pinion is not interfered with by the spring and the spring is permitted to exert sufficient pressure upon the pinion at the proper time to insure its return to normal position as shown in Figs. 1 and 5.

The pinion is held out of engagement with the flywheel regardless of the engine's oper-

ation and of the operator's carelessness in not restoring the parts under his control to normal position. Moreover, the engagement of the pinion with the flywheel cannot be established until after the completion of the cycle above described. The spring must be of sufficient tension to effectively restore the pinion to its normal position against the stop nut but the same must not interfere with the throwout of the pinion in the demeshing operation or prevent sufficient longitudinal movement of the pinion to enable the pinion to be caught by the latch. Consequently, my novel means provides the requisite spring tension against the pinion for restoring it to normal position and a minimum or practically no tension at the initiation of the throwout of the pinion.

In Figs. 10 and 11 I have shown a modified form of construction whereby the length of the drive is considerably reduced. The particular length of the drive of Figs. 1 to 9 is dependent upon the length of the slots 18. In order to shorten the drive, I attain, in the modified structure, the proper slot length by providing similar slots in both the armature shaft and in the sleeve. Accordingly, the armature shaft is provided with a longitudinal slot 29 at one end of which the transverse pinion 17 is located, and the sleeve with the longitudinal slots 30, such slots 29 and 30 being in alignment as shown in Fig. 11. In other respects, the construction and operation are the same as that hereinbefore described.

I do not herein broadly claim the construction and the arrangement of the drive including the longitudinally shiftable sleeve or driving member or pinion thereon and the catch device for holding the pinion in demeshed position while the screw shaft or sleeve is still shifted to cranking position as the same represent subject matter of my prior applications for patent including application filed on January 4, 1923, Serial No. 610,672, the present application being directed to the particular invention pointed out in the claims herein.

I claim:

1. An engine starter drive including a longitudinally slidable rotatable shaft, a driving member mounted thereon for rotary movement therewith and for longitudinal movement thereof, and yielding means acting on the driving member tending to hold it to a normal position on the shaft and acting with a variable degree of pressure according to the longitudinal position of the shaft and with the least pressure in cranking position.

2. An engine starter drive including a rotatable and longitudinally slidable shaft, a driving member mounted thereon for rotary movement therewith and for longitudinal movement thereof, and yielding means

acting on the driving member tending to hold it towards one end of the shaft and acting with a variable degree of pressure according to the longitudinal position of the shaft and with the least pressure in cranking position. 70

3. An engine starter drive including a longitudinally slidable rotatable shaft, a driving member mounted thereon for rotary movement therewith and for automatic disengagement from a member of the engine to be started when such engine starts on its own power, and yielding means cooperating with the driving member and tending to hold it to a normal position on the shaft 75 with a variable tension but with the least tension when about to be disengaged from the engine member. 80

4. An engine starter drive including a longitudinally slidable rotatable shaft, a driving member mounted thereon for rotary movement therewith and for longitudinal movement thereof, a stop means on the shaft, and a yielding means cooperating with the driving member and tending to hold it in normal position against the stop means and acting with a variable degree of pressure according to the longitudinal position of the shaft and with the least pressure in cranking position. 90 95

5. An engine starter drive including a longitudinally slidable rotatable shaft, a driving member mounted thereon for rotary movement therewith and for longitudinal movement thereof, and a spring cooperating 100 with the driving member and tending to hold it in a normal position on the shaft and acting with a variable degree of pressure according to the longitudinal position of the shaft and with the least pressure in 105 cranking position.

6. An engine starter drive including a longitudinally slidable rotatable shaft, a driving member mounted thereon for rotary movement therewith and for longitudinal movement thereof, a stop means on the shaft, and a coiled spring encircling the shaft and cooperating with the driving member and tending to hold it in a normal position against the stop means and acting 110 with a variable degree of pressure according to the longitudinal position of the shaft and with the least pressure in cranking position. 115

7. An engine starter drive including a longitudinally slidable rotatable shaft mounted for rotary and longitudinal movement, a driving member mounted thereon for rotary movement therewith and longitudinal movement thereof, and adapted to engage a member of the engine to be started, and a yielding means cooperating with the driving member and tending to hold it in a normal position on the shaft, such yielding means being constructed and arranged 120 125 130

- to act with variable effect on the driving movement therewith and for longitudinal member but with the least effect when about to be disengaged from the engine member. 8. An engine starter drive including a driving shaft, a hollow shaft mounted thereon for rotary movement therewith and longitudinal movement thereof, a driving member mounted on the hollow shaft for rotary movement therewith and longitudinal movement thereof, and yielding means cooperating with the driving member and acting thereon with a pressure which varies according to the position of the hollow shaft on the driving shaft. 9. An engine starter drive including a driving shaft, a hollow shaft splined thereon for rotary movement therewith and longitudinal movement thereof, a driving member mounted on the hollow shaft for rotary movement therewith and longitudinal movement thereof, and a coiled spring bearing at one end against the driving shaft and at its other end acting on the driving member with a pressure which varies according to the position of the hollow shaft on the driving shaft. 10. An engine starter drive including a driving shaft, a hollow shaft splined thereon for rotary movement therewith and longitudinal movement thereof, a driving member mounted on the hollow shaft for rotary movement therewith and longitudinal movement thereof, a stop means on the hollow shaft, and a coiled spring bearing at one end against the driving shaft and at its other end against the driving member to normally hold it against the stop means. 11. An engine starter drive including a longitudinally slideable rotatable shaft, a driving member mounted thereon for rotary movement therewith and for longitudinal movement thereof for engagement with a member of the engine to be started, a yielding means acting on the driving member tending to hold it to a normal position on the shaft and towards the engine member, the degree of pressure of such yielding means being varied according to the different positions of the movable parts in the operation of the drive and being the least when the parts are in cranking position. 12. An engine starter drive including a longitudinally slideable rotatable shaft, a driving member mounted thereon for rotary movement therewith and for longitudinal movement thereof, and yielding means acting on the driving member tending to hold it towards one end of the shaft, the degree of pressure of such yielding means upon the driving member being varied according to the different positions thereof and being the least when the parts are in cranking position. 13. An engine starter drive including a longitudinally slideable rotatable shaft, a driving member mounted thereon for rotary movement therewith and for longitudinal movement thereof, a stop means on the shaft, and a yielding means cooperating with the driving member and tending to hold it in normal position against the stop means, the degree of pressure of such yielding means being varied according to the position of the driving member on the shaft and being the least when the parts are in cranking position. 14. An engine starter drive including a longitudinally slideable rotatable screw shaft, a driving member threaded thereon for rotary movement therewith and longitudinal movement thereof, a stop means at one end of the threads, and yielding means cooperating with the driving member and tending to normally hold it against the stop means, the tension of said yielding means being varied according to the position of the driving member with respect to the member of the engine with which it is engaged for cranking purposes and being the least when the parts are in cranking position. 15. An engine starter drive including a rotatable driving shaft, a hollow shaft mounted thereon for longitudinal movement thereof and rotary movement therewith, a driving member mounted on the hollow shaft for longitudinal movement thereof and rotary movement therewith, and a spring bearing at its opposite ends against the driving shaft and the driving member respectively and exerting a tension upon the driving member according to its relative position on the hollow shaft. 16. An engine starter drive including a rotatable driving shaft, a hollow shaft mounted thereon for longitudinal movement thereof and rotary movement therewith, a driving member mounted on the hollow shaft for longitudinal movement thereof and rotary movement therewith, a stationary spring abutment upon the driving shaft, and a coiled spring encircling the hollow shaft and bearing at its opposite ends against said abutment and the driving member respectively. 17. An engine starter drive including a rotatable driving shaft, a hollow shaft mounted thereon for longitudinal movement thereof and rotary movement therewith, a driving member mounted on the hollow shaft for longitudinal movement thereof and rotary movement therewith, said driving shaft having a radial projection and said hollow shaft having a longitudinal slot through which such projection extends, and a spring bearing at one end against said projection and at the other end against the driving member. 18. An engine starter drive including a rotatable driving shaft, a hollow shaft mounted thereon for longitudinal movement thereof and rotary movement therewith, a

driving member mounted on the hollow shaft for longitudinal movement thereof and rotary movement therewith, a pin extending transversely of the driving shaft, said hollow shaft having longitudinal slots through which the pin extends, and a spring bearing at one end against said pin and at the other end against the driving member.

19. An engine starter drive including a rotatable driving shaft, a hollow shaft mounted thereon for longitudinal movement thereof and rotary movement therewith, a driving member mounted on the hollow shaft for longitudinal movement thereof and rotary movement therewith, said driving shaft having a radial projection and said hollow shaft having a longitudinal slot through which such projection extends, a spring abutment connected with said projection and a spring bearing at one end against the abutment and at the other end against the driving member.

20. An engine starter drive including a rotatable driving shaft, a hollow shaft mounted thereon for longitudinal movement thereof and rotary movement therewith, a driving member mounted on the hollow shaft for longitudinal movement thereof and rotary movement therewith, said two shafts having pin and slot connection, and a spring connecting between the pin and driving member.

21. An engine starter drive including a rotatable shaft, a driving member mounted thereon for rotary movement therewith and for longitudinal movement thereof, means for holding the driving member in a retracted position on the shaft, and yielding means acting on the driving member tending to hold it to a normal position on the shaft, and acting with a variable degree of pressure.

22. An engine starter drive including a rotatable shaft, a driving member mounted thereon for rotary movement therewith and for longitudinal movement thereof to engage a member of the engine to be started, a stop means on the shaft, means on the shaft for engaging the driving member in its longitudinal movement after disengagement from the engine member and for holding it in retracted position away from the stop means, and yielding means acting on the driving member tending to hold it to a normal position against such stop means, the degree of pressure of such yielding means being varied.

23. An engine starter drive including a screw shaft, a pinion threaded thereon for rotary movement therewith and for longitudinal movement thereof, into engagement with a member of the engine to be started, a stop on the shaft against which stop the pinion is normally positioned, means on the shaft for holding the driving member in retracted position on the shaft after disengagement from the engine member, and a

spring normally pressing the pinion against the stop, the degree of pressure of such spring being varied.

24. An engine starter drive including a rotatable driving shaft, a hollow shaft mounted thereon for longitudinal movement thereof and rotary movement therewith, manually operated means for bodily shifting the hollow shaft and driving member longitudinally of the driving shaft, means for holding the driving member in a disengaged position before the hollow shaft is returned to normal position, and a spring carried by the driving shaft and cooperating with the driving member to exert a tension thereon dependent upon the relative positions of the hollow shaft and driving member.

25. An engine starter drive including a rotatable driving shaft, a hollow shaft mounted thereon for longitudinal movement thereof and rotary movement therewith, a driving member mounted on the hollow shaft for longitudinal movement thereof and rotary movement therewith, manually operated means for bodily shifting the hollow shaft and driving member longitudinally of the driving shaft, means for holding the driving member in a disengaged position before the hollow shaft is returned to normal position, a drum secured to the hollow shaft and extending over said holding means, and a spring carried by the driving shaft and extending over said drum and bearing against the driving member.

26. An engine starter drive including a rotatable driving shaft, a hollow shaft mounted thereon for longitudinal movement thereof and rotary movement therewith, a driving member mounted on the hollow shaft for longitudinal movement thereof and rotary movement therewith, manually operated means for bodily shifting the hollow shaft and driving member longitudinally of the driving shaft, means for holding the driving member in a disengaged position before the hollow shaft is returned to normal position, said holding means comprising a latch pivoted on the hollow shaft and adapted to engage the driving member, a spring tending to force the latch to engaging position, a drum secured to the hollow shaft and extending over the latch, said

spring being interposed between the drum and the latch, and a spring connected at one end to the driving shaft and bearing at its other end against the driving member.

27. An engine starter drive including a rotatable driving shaft, a hollow screw shaft splined thereon for longitudinal movement thereof and rotary movement therewith, a pinion threaded on the screw shaft, said screw shaft having a stop at one end, and a

spring connected at one end to the driving shaft and cooperating with the pinion to normally hold it against such stop.

28. An engine starter drive including a 5 rotatable driving shaft, a hollow screw shaft splined thereon for longitudinal movement thereof and rotary movement therewith, a pinion threaded on the screw shaft, said screw shaft having a stop at one end, and 10 a coiled spring encircling the screw shaft and connected at one end to the driving shaft and bearing at its other end against the pinion.

29. An engine starter drive including a 15 rotatable driving shaft, a hollow screw shaft splined thereon for longitudinal movement thereof and rotary movement therewith, a pinion threaded on the screw shaft, said screw shaft having a stop at one end, said 20 driving shaft having a projection and said screw shaft having a longitudinal slot through which such projection extends, and a spring connected at one end to said projection and bearing at its other end against the pinion.

30. An engine starter drive including a longitudinally slidable rotatable shaft having a stop at one end, a driving member mounted on the shaft for rotary movement 30 therewith and longitudinal movement thereof, means for moving the driving member longitudinally to disengage it from a member of the engine to be started when the latter becomes the driver, and yielding 35 means cooperating with the driving member to normally hold the same against said stop and acting on such driving member with a pressure which varies according to the posi-

tion of the driving member on the shaft.

31. An engine starter drive including a 40 longitudinally slidable rotatable shaft having a stop at one end, a driving member mounted on the shaft for rotary movement therewith and longitudinal movement thereof, and a spring cooperating with the driving member to normally hold the same 45 against said stop, whereby the tension of the spring is varied according to the longitudinal position of such shaft.

32. An engine starter drive including a 50 central rotatable driving shaft, a sleeve mounted on such shaft to slide longitudinally thereon and to be driven thereby, a driving member mounted on the sleeve for 55 rotary movement therewith and for longitudinal movement thereof, and yielding means acting on the driving member tending to hold it to a normal position on the sleeve and acting with a variable degree of pressure according to the longitudinal position of such sleeve upon its shaft and with 60 the least pressure in cranking position.

33. An engine starter drive including a central rotatable driving shaft, a screw 65 threaded sleeve mounted on such shaft to slide longitudinally thereon and to be driven thereby, a driving member threaded on the sleeve for rotary movement therewith and for longitudinal movement thereof, and 70 yielding means acting on the driving member tending to hold it to a normal position on the sleeve and acting with a variable degree of pressure according to the longitudinal position of such sleeve upon its shaft and with the least pressure in cranking position.

WILLIAM L. McGRATH.
